Term of patent 14 years

(Cl. D81—10)

FIG.1.

FIG.5.

FIG.2.

FIG.3.

FIG.4.

FIG. 1 is a perspective view of an electric toaster embodying the new design, portions of the casing being broken away to indicate an indeterminate width and an indeterminate number of toast-receiving openings;

FIG. 2 is an elevational view of the end of the toaster not shown in FIG. 1;

FIG. 3 is an elevational view of the side of the toaster not shown in FIG. 1;

FIG. 4 is an enlarged fragmentary sectional view, taken along the line IV—IV of FIG. 3, looking in the direction indicated by the arrows; and,

FIG. 5 is an enlarged fragmentary sectional view, taken along the line V—V of FIG. 3, looking in the direction indicated by the arrows.

The dominant features of the design reside in the portions shown in full lines.

I claim:

The ornamental design for an electric toaster, substantially as shown and described.
